UNITED STATES PATENT OFFICE.

ARTHUR DANSEREAU, OF SOUTHBRIDGE, MASSACHUSETTS.

SHIPPING-TAG.

1,198,826.

Specification of Letters Patent. Patented Sept. 19, 1916.

Application filed March 23, 1905. Serial No. 251,568.

To all whom it may concern:

Be it known that I, ARTHUR DANSEREAU, a citizen of the United States, residing at Southbridge, in the county of Worcester and State of Massachusetts, have invented a new and useful Shipping-Tag, of which the following is a specification.

This invention relates to that class of tags which are known as shipping tags.

10 The especial object of this invention is to provide a strong, simple and inexpensive tag which is especially adapted to be manufactured by machinery.

To these ends, this invention consists of 15 the tag as an article of manufacture and of the combinations of parts therein as herein-after described and more particularly pointed out in the claim at the end of this specification.

20 In the accompanying drawing, Figure 1 is a perspective view showing the relation of the parts in applying the metal clip to the card of a shipping tag according to this invention. Fig. 2 is a similar view showing 25 the tying string. Fig. 3 is a view showing the metal clip bent over into place with the metal punched down from the top leg of the clip to extend down through holes in the card and bottom leg of the clip. Fig. 4 is a 30 view of the complete article, and, Fig. 5 is an enlarged fragmentary view showing the punched down tube which projects down from the top leg of the clip.

In that class of tags to which this invention relates, the form of tag which is now 35 most widely employed comprises a pasteboard card having a hole near one end reinforced by a perforated disk of heavy cardboard material. The tying string of this 40 ordinary form of tag is passed through the hole and ordinarily tied by hand.

The especial object of the present invention is to provide a tag reinforced by a metal clip so that the same will be much stronger 45 than the tags now ordinarily employed and to provide for assembling the parts and for fastening the tying string in place in a simple and direct way so that the tags will be especially adapted to be manufactured by machinery.

50 In making tags according to this invention, the cards may be stamped or cut out in any desired manner and have any desired reading matter printed thereon.

55 The metal clip which reinforces the card and preferably constitutes the means for

fastening the tying string, is cut from a coil of sheet metal and is fed along with the card. The clip is punched out so as to be provided with top and bottom legs separated 60 by marginal notches and the top leg is provided with a perforation and the bottom leg with a somewhat larger perforation.

The tying string is preferably fed into proper place in connection with the clip and 65 the legs of the clip are bent over to embrace the end of the card. The metal of the top leg of the clip is then punched down to extend down through the hole in the body of the card and through the hole in the bottom 70 leg of the clip and is then riveted down so that the clip is eyeleted onto the card to be rigidly attached thereto and the clip also serves to fasten the tying string.

Referring to the accompanying drawing 75 for a detailed description of a tag construction of this invention, as shown in Fig. 1, A designates the card. The metal clip B has a bottom leg 10 and top leg 11 which at first stand in line with each other. The bottom 80 leg 10 is provided with a perforation 14 and the top leg 11 is provided with a small perforation 12 which registers with the hole 13 near the end of the card. The two legs of the clip are separated by marginal notches 85 so as to form an easy fold line, and so that a tying string S can be inserted between the clip and tag and accurately held in place. As the tying string projects out through the notches, as shown in Fig. 4, it will be seen 90 that if any strain is put on the string it will rest against the metallic edges of the clip instead of on the card. After the tying string S is fitted into place as shown in Fig. 2, the clip is placed onto the edge of the card 95 preferably by means of suitable rollers and a punch is employed for punching down a projection or tube 15 from the top leg of the clip which extends down through the card and through the bottom leg of the clip. 100 This tube is then riveted back onto the bottom leg of the clip as shown in Fig. 4. Thus a rivet 15 is produced having two flanges 10 and 11 between which is a recess for the string.

These successive operations are preferably performed by an automatic machine and the tag is completed without the use of manual operation.

110 In a tag as thus constructed, it will be seen that the end of the card is reinforced and strengthened by the metal clip, that the

parts of the metal clip are neatly and strongly eyeleted together, and that the metal clip also serves to fasten the tying string.

5 Having thus fully described my invention, what I claim and desire to secure by Letters Patent of the United States is:

The combination with the tag or label proper, and the attaching string, of the U-shaped piece or strip clasping a marginal portion of the tag or label proper and an intermediate portion of the length of the

string and clamping the string within its bend or bight, with its respective limbs permanently secured at intermediate points in their lengths to the opposite surfaces of the tag or label proper.

In testimony whereof I have hereunto set my hand in the presence of two subscribing witnesses.

ARTHUR DANSEREAU.
